United States Patent Office

Des. 227,217

Patented June 12, 1973

227,217

CLEAT

Charles Otto Pick, 10060 SW. Durham Road,
Tigard, Oreg. 97223

Filed Nov. 5, 1971, Ser. No. 196,252

Term of patent 14 years

Int. Cl. D8—08

U.S. Cl. D8—232

FIG. 1 is a top plan view of a cleat showing my new design;

FIG. 2 is an end elevation view, the opposite end being the same as the end shown;

FIG. 3 is a side elevation view, the opposite side being the same as the side shown;

FIG. 4 is a view on the line 4—4 in FIG. 1;

FIG. 5 is a bottom plan view; and

FIG. 6 is a perspective view.

I claim:

The ornamental design for a cleat, substantially as shown and described.
